UNITED STATES PATENT OFFICE.

CLINTON E. LARRABEE, OF BINGHAMTON, NEW YORK, ASSIGNOR TO INTERNATIONAL TIME RECORDING COMPANY OF NEW YORK, OF ENDICOTT, NEW YORK, A CORPORATION OF NEW YORK.

DRIVING DEVICE FOR PROGRAM CLOCKS.

Application filed October 28, 1924. Serial No. 746,295.

This invention relates to improvements in program clocks and more particularly to improvements in the driving mechanism for clocks of this type whereby the program 5 wheel or wheels may be driven from a clock train without the attendant creeping motion of the wheels which is usually secured when the wheels are driven directly from the clock driven devices.

According to the present invention provision is made for advancing the program wheels by a stepped rapid movement instead of a constant slow movement and the motion is secured by the provision of a novel driving connection operating in combination 15 with the program driven elements and the clock train driving elements.

In the drawings,

Fig. 1 is a front view of a program device 20 provided with my improvement.

Fig. 2 is a side view of the driving connections which impart a jump movement to the program wheels.

Figs. 3 and 4 are detail top views of the 25 parts in different operative positions.

In more detail, the program device proper is of conventional form including program discs 10 adapted to control the program contacts 11. The discs 10 are driven by a gear 12 which has meshed with it a small pinion 13 driven by bevel gearing 14. One of the bevel gears 14 is fixed to a shaft 15 which extends upwardly as shown in Fig. 2 and has a collar 16 secured to it by a screw 17. 30 18 denotes a fixed bracket plate preferably recessed with a rectangular opening to receive a collar member 19. This collar in turn receives a second collar member 20, the two collars being secured together by a screw 21. Fast to the collar member 20 is a ratchet disc 22. Cooperating with the ratchet disc is a pawl 23 pivotally carried by a lever or crank member 24 which is securely fast to the collar 16 which, as previously stated, is secured to shaft 15. The 35 pawl 23 is provided with a pin 25 extending into an angular slot 26 in a driving lever or double armed member 27. Part 27 is

secured to a collar-like member 28 which is freely rotatable upon the upper end of shaft 50 15 and slotted at its upper end to receive the cross pin 29 of a universal joint which is carried by the clock driven shaft 30. The shaft 30 will hereinafter be termed the main clock driving member for the program device. The extended ends of the two members 27 and 24 are suitably connected by a spring 31.

In operation the main clock driving shaft 30 gradually advances in a counterclockwise direction. The to be driven shaft 15 is held against rotation by pawl 23 engaging the ratchet 22. As 27 is rotated, the spring 31 is put under increased tension and the pawl 23 is gradually withdrawn from engagement with the ratchet by reason of the camming action of slot 26 upon pin 25. When the pawl reaches a position clear of the ratchet (see Fig. 4) the spring tension of spring 31 acts to swing arms 24 in an 60 65 anticlockwise direction ultimately reengaging the pawl 23 with the next ratchet tooth. In this way the driven arm 24 jumps the program drive shaft 15 forward step by step with steps of definite and fixed magnitude.

What I claim is—

1. In a device of the class described, in combination, a clock driving shaft, a program device, means for periodically imparting movement derived from continuous movement of the driving shaft to said program device in steps of definite magnitude, said means comprising a fixed ratchet, a member connected to drive the program device and having a pawl cooperating with said ratchet, a member driven by the clock driving shaft with provisions for controlling the coaction of the pawl and ratchet, and a spring connecting the said members and 80 85 adapted to advance the first mentioned member upon the release of the pawl from the ratchet.

2. In a device of the class described in combination with a clock driving shaft, a program device, means driven in unison with 90 95

said clock shaft, means movable in unison with the program devices, a fixed ratchet, a pawl associated with said last mentioned means and arranged for cooperation therewith, means carried by the first mentioned means for swinging the pawl into or out of cooperation with the ratchet and a resilient

means receiving energy upon the advance of the clock driving shaft for imparting movement to the said pawl upon its release from said ratchet. 10

In testimony whereof I hereto affix my signature.

CLINTON E. LARRABEE.
